UNITED STATES PATENT OFFICE.

EDWIN A. REETZ, OF HOOPER, NEBRASKA.

HOISTING MECHANISM.

1,286,773.

Specification of Letters Patent.

Patented Dec. 3, 1918.

Application filed April 22, 1918. Serial No. 230,073.

To all whom it may concern:

Be it known that I, EDWIN A. REETZ, a citizen of the United States, residing at Hooper, in the county of Dodge and State 5 of Nebraska, have invented certain new and useful Improvements in Hoisting Mechanism, of which the following is a specification, reference being had to the accompanying drawings.

10 This invention relates to certain improvements in hoisting boxes on wagons or trucks and it is an object of the invention to provide a device of this general character having novel and improved means whereby the 15 body of the wagon or truck may be readily and conveniently moved or tilted into dumping position.

It is also an object of the invention to provide a novel and improved device of this general character having means for imparting the requisite movement to the body of the wagon or truck, said means including a mechanism which renders said means normally inoperative.

25 Another object of the invention is to provide a novel and improved device of this general character including a body mounted for swinging movement in a vertical plane together with means for causing said body 30 to assume a tilting position and wherein means are employed for retarding the return movement of the body.

The invention consists in the details of construction and in the combination and arrangement of the several parts of my improved hoist whereby certain important advantages are attained and the device rendered simpler, less expensive and otherwise more convenient and advantageous for use,

40 as will be hereinafter more fully set forth.

The novel features of my invention will hereinafter be definitely claimed.

In order that my invention may be the better understood, I will now proceed to 45 describe the same with reference to the accompanying drawings wherein:

Figure 1 is a view in side elevation illustrating a hoist constructed in accordance with an embodiment of my invention;

50 Fig. 2 is a fragmentary view in elevation illustrating the mounting of the mast or standard as herein employed;

Fig. 3 is a fragmentary view partly in section and partly in top plan illustrating 55 the connection of the swinging body with the mast or standard;

Fig. 4 is a view partly in elevation and partly in section illustrating the means for raising or tilting the wagon or truck body;

Fig. 5 is a view partly in vertical section 60 and partly in elevation of the structure illustrated in Fig. 4;

Fig. 6 is a fragmentary view partly in top plan and partly in section of the structure illustrated in Fig. 4 with the driving 65 member in inoperative position; and

Fig. 7 is a fragmentary view partly in cross section and partly in elevation of the structure as illustrated in Fig. 6.

As disclosed in the accompanying drawings 70 F denotes a wagon or truck frame of any desired construction and which has its forward end at substantially the transverse center of the frame provided with the upstanding lug or ear 1 with which is pivotally engaged as at 2 the lower end portion of the upstanding mast or standard 3. The mast or standard 3 is adapted to have swinging movement in a vertical plane or in a plane longitudinally of the frame F. The 75 mast or standard 3 adjacent each of its opposite ends is provided with an opening 4 in which is rotatably positioned a pulley 5.

B denotes a wagon or truck body of any 80 desired type overlying the frame F and having its rear end portion hingedly connected as at 6 with the rear portion of the frame F as is particularly illustrated in Fig. 1. The body B is capable of swinging movement in a vertical plane. The lower 85 portion of the body B at the forward end thereof is provided with a pair of spaced guide arms or members 7 having sliding engagement with a mast or standard. The forward end of the body B between the arms 90 or members 7 is also provided with the outwardly directed lug 8 or the like to which is suitably engaged an end portion of a flexible member M. The member M is disposed over the upper pulley 5 and then around the 95 lower pulley 5. From the lower end portion of the mast or standard 3 the member M extends rearwardly and is engaged with the winding drum D suitably supported by the frame F and mounted for movement around 100 a vertically disposed axis. Upon rotation of the drum D in one direction the member M is wound therearound which results in an elevation of the forward end portion of the body B whereby said body is moved into 105

dumping position.

The central portion of the drum D is pro-

vided with a worm gear 9 adapted to be engaged by the worm 10 carried by the shaft 11. An end portion of the shaft 11 is provided with an operating crank 12 whereby the desired rotation may be imparted to the shaft 11. The shaft 11 is disposed transversely of the frame F and is rotatably supported by the rotatable bearings 14 suitably supported by the frame F. The shaft 11 is eccentric to the axes of the bearings 14 so that upon movement of the bearings 14 in one direction the worm 10 will be disengaged from the gear 9, and vice versa.

15 denotes a rod disposed transversely of the frame F and provided at its opposite ends with the laterally directed arms 16 suitably secured to the bearings 14 so that said bearings will be caused to rotate in unison and in the same general direction. The 20 outer face of one of the bearings 14 has engaged therewith, an operating member or lever 17 to effect the desired rotation of the bearings 14 when it is desired to cause the worm 10 to engage the gear 9 or otherwise.

25 The arms 16 are of such a length as to cause the rod 15 to bear upon a side face of the gear 9 when the bearings 14 are rotated in one direction to disengage the worm 10 from the gear 9. In the present embodiment 30 of the invention this engagement of the rod 15 with the gear 9 is obtained upon forcing the member or lever 17 rearwardly. When the rod 15 is in contact with the gear 9 it serves as a brake element whereby the lowering or dropping movement of the body B is retarded. It is to be understood that the 35 body B returns to its normal or substantially horizontal position by gravity and the speed of its falling or return movement can be readily controlled by the amount of pressure upon the gear 9 by the rod 15.

40 From the foregoing description, it is thought to be obvious that a hoist con-

structed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination, a driven element, a driving element, rotatable bearings for the driving element, said driven element being eccentric to the axes of the bearings, means connecting the bearings for causing the same to rotate in unison and in the same general direction, means carried by one of the bearings for rotating the same, and means for connecting the bearings for braking action upon the driven element upon movement of the bearings in one direction.

2. In combination, a driven element, a driving element, rotatable bearings for the driving element, said driven element being eccentric to the axes of the bearings, a rod connecting the bearings for causing the same to rotate in unison and in the same general direction, means carried by one of the bearings for rotating the same, and rods for connecting the bearings for braking action upon the driven element upon movement of the bearings in one direction.

In testimony whereof I hereunto affix my signature in the presence of two witnesses.

EDWIN A. REETZ.

Witnesses:

A. M. TILLMAN,
W. F. BASLER.
